his Attorney.

UNITED STATES PATENT OFFICE.

MARTIN KELP, OF PARIS, OHIO.

FLOW.

Application filed January 18, 1924. Serial No. 686,994.

To all whom it may concern:

Be it known that I, MARTIN KELP, a citizen of the United States, residing at Paris, in the county of Stark and State of Ohio, 5 have invented a new and useful Plow, of which the following is a specification.

This invention relates to improvements in plows, and more especially to a plow known in the art as a reversible or hillside plow.

10 One object of this invention is to produce a highly practical plow of the character indicated in which the mold-board of the plow is pivotally connected to the standard and has its axis substantially parallel with 15 the draft-line of the plow, and to enable the mold-board, upon raising said standard, to be actuated circumferentially of said axis and under the standard from its position at one side into position at the opposite side 20 of the plow.

Another object is to render the connection between the mold-board and the standard simple and durable in construction, and to provide simple and inexpensive means for 25 holding the mold-board and attached plow-share in the required position.

Another object is to attach and fit the plow-share to the mold-board in such a manner that, in plowing, there is no liability 30 of loosening or displacement of the plow-share in relation to the mold-board, nor strain upon the bolts or screws employed in securing the plow-share to the mold-board.

Another object is to so contour and relatively arrange the plow-share and mold-board that the plow shall operate more uniformly and with greater efficiency than hillside plows heretofore made, and that the mold-board and plow-share shall adequately 40 cooperate in turning over the furrow-slice and in the breaking up or disintegration of turned up lumps of earth.

Another object is to facilitate the assemblage of the component parts of my improved plow, and to reduce, to a minimum, the strain upon said parts during the operation of the plow.

With these objects in view, and to attain any other object hereinafter appearing, this 50 invention consists in certain features of construction, and combinations and relative arrangements of parts, hereinafter described in this specification, pointed out in the claims, and illustrated in the accompanying drawings.

In said drawings, Figure 1 is a side elevation, partly in section, of the greater portion of a hillside plow embodying my invention. Fig. 2 is a horizontal section taken along the line 2—2 in Fig. 1. Fig. 3 is a 60 section and front view taken along the line 3—3 in Fig. 1. Fig. 4 is a rear end view and shows the mold-board in solid lines at the left-hand side of the plow and in broken lines at the right-hand side of the plow. 65 Fig. 5 is a section taken along the line 5—5 in Fig. 4, looking downwardly. Fig. 6 is a side view of the mold-board and attached plow-share. Figs. 7 and 8 are vertical sections taken along the line 7—7 and line 8—8 70 respectively in Fig. 6, looking forwardly. Figs. 9 and 10 are vertical sections taken along the line 9—9 and line 10—10 respectively in Fig. 6, looking rearwardly.

Referring to said drawings, A indicates 75 the draft-beam; B the standard; C, the mold-board, and D, the plow-share.

The draft-beam A is rendered rigid with the standard B in any approved manner, and the provision of said draft-beam with 80 handles or draft-appliances is too well understood in the art to require illustration and description in this specification.

The mold-board C is shown arranged in 85 Figs. 1, 2, 3, 4 and 5, and in solid lines in Fig. 4, at the left-hand side of the plow.

The mold-board C (see Figs 1, 2 and 5) has a forward end member 15 which extends forwardly of the lower end portion of the standard B, and the share D is seated on 90 and secured to said member 15 as will hereinafter appear.

The lower end portion of the standard (see Fig. 5) is provided, at the front of the standard, with a forwardly projecting pivotal member 16 which is arranged substantially parallel with the draft-line of the plow and extends into a corresponding hole 17 formed in the member 15 of the mold-board, and said member 15 has a bearing on 95 said pivotal member. It will be observed, therefore, that the member 15 of the mold-board is pivoted to the standard B and has its axis substantially parallel with the draft-line of the plow.

A bracket 18 (see Figs. 1, 4 and 5) is arranged at the rear end of the standard B and provided with a pivotal member 19 which is in line endwise with the pivotal member 16 and projects into and has bear- 100 105 110

ing in the lower end portion of the standard. Obviously the bracket 18 has its axis coincident with the axis of the member 15 of the mold-board and is, therefore, substantially parallel with the draft-line of the plow.

The bracket 18 is arranged at the inner side of the rear end portion of the mold-board and has two spaced arms 20 and 21 which (see Fig. 4) extend adjacent opposite longitudinal edges respectively of the mold-board, and the mold-board is removably secured, by suitably applied screws 22, to said arms.

The standard B has a rearwardly projecting lug 23 formed at the rear and substantially centrally between the upper and lower ends of the standard, and the bracket 18 is held in the required position by means preferably comprising a latch 25 which (see Figs. 2 and 4) is mounted on said lug and pivoted, as at 26, to said lug, and has its axis substantially at a right angle to the axis of said bracket. Said latch comprises two hooks 28 and 29 which are spaced circumferentially of the axis of the latch and arranged to operatively engage the one with the arm 20, or the other with the arm 21, according as the mold-board is in position at the one or the other side of the plow. The operative engagement of the hook 28 with the bracket-arm 20 is shown in Fig. 2 and in solid lines in Fig. 4 wherein the mold-board is shown arranged in solid lines at the left-hand side of the plow. The hook 28 is shown partly broken away and in section in Fig. 4 to more clearly illustrate the operative engagement of said hook with the arm 20 as required to lock or hold the mold-board in position at the left-hand side of the plow.

The beam A and attached standard B are, of course, raised to permit the actuation of the mold-board C (with the share D attached) circumferentially of the pivotal members 16 and 19 and under the standard from its position at one side into position at the opposite side of the plow.

When the mold-board is in position at the right-hand side of the plow, as illustrated in broken lines in Fig. 4, the latch 25 is actuated into the position required to effect operative engagement by its hook 29 with the arm 21 of the bracket 18.

To prevent undue strain upon the screws 22 the bracket 18 (see Figs. 4 and 5) is tied, at a point between the arms 20 and 21, to the mold-board C by means comprising a tie-rod 30. Preferably the rod 30 extends loosely through and rearwardly of the bracket 18, and a nut 31 is threaded onto said rod at the rear side of said bracket. The rod 30 extends through and forwardly of a lug 32 formed at the inner side of and on the mold-board C at a point spaced for-

wardly from the bracket 18, and said rod has a shoulder 33 arranged at and abutting against the forward side of said lug.

By the hereinbefore described construction it will be observed that only the removal of the screws 22 and nut 31 is required to release the mold-board from the bracket 18 and to render said bracket removable from the standard B.

As shown in Fig. 8, the outer side 35 of the forward end member 15 of the mold-board faces upwardly and laterally outwardly and is preferably curved inwardly and transversely and forms a seat for the share D, and the mold-board is provided, at the rear end of said seat, with a forwardly and inwardly facing and preferably undercut shoulder 36 which extends transversely of the mold-board, as shown more clearly in Fig. 5, and said share has a beveled rear transverse edge arranged opposite and extending longitudinally of and abutting against said shoulder. Preferably the mold-board is substantially uniform in width from the shoulder 36 to the rear end portion of the mold-board.

The share D (see Fig. 5) is provided with a rearwardly facing and preferably undercut shoulder 37 arranged forward of and spaced from the pivotal member 16 of the standard B and abutting against a correspondingly arranged forwardly facing end face 38 formed on the member 15 of the mold-board. Said member 15 is secured, between the shoulders 36 and 37, to the share D preferably removably by bolts or screws 39.

The share D extends forwardly of the member 15 of the mold-board and is preferably contoured as required to terminate at its forward extremity in a point 40, as shown in Figs. 1, 2, 5 and 6.

The share D, in order to render more especially efficient my improved hillside plow, has two fin-like flanges or projecting members 41 and 42 which overlap, as at 43, the forward end portion of opposite longitudinal edges respectively of the mold-board, adjacent opposite ends respectively of the shoulder 36 as shown in Figs. 1, 2 and 6, and preferably said projecting members 41 and 42 are widest at their rear end portions and converge and are gradually reduced in width from said end portions toward the point 40 or forward extremity of the share. The relative arrangement of the parts is such that when the mold-board is in position at the left-hand side of the plow, as shown in Figs. 1, 2 and 3, the projecting member 41 of the share D is at the top and right-hand side of said share and the projecting member 42 of said share is at the bottom of the share.

It will be observed that the seating of the share D on the member 15 of the mold-

board, the abutting of the rear end of said share against the undercut shoulder 36 on the mold-board, the abutting of the undercut shoulder 37 on said share against the 5 forward end face of the member 15 of the mold-board, and the overlapping of the longitudinal edges of the mold-board by members or portions of said share, all participate in forming a simple and durable construction by which strain upon the bolts or screws 39 is successfully prevented. The shoulder 36 on the mold-board is arranged wholly rearward of the pivotal connection 16 between the standard B and the forward member 15 of the mold-board and preferably wholly rearward of the screws 39, and by the hereinbefore described construction it will be observed that the plow-share is firmly secured to said member of the mold-board and that the rear beveled edge of said share extends transversely of the share at the rear extremity of the seat formed by the side 35 of said member of the mold-board and is overlapped by the undercut shoulder 36 on the mold-board so that said shoulder not only serves as an abutment for and extends longitudinally of said rear edge of the plow-share but also serves to hold the plow-share rigidly, at the rear end of 30 said share, to said seat.

The mold-board C has an outer side 43 which extends rearwardly from the share D and faces laterally outwardly and upwardly and is curved inwardly and transversely to form a hollow extending rearwardly from the shoulder 36 on the mold-board and gradually increasing in depth in a rearward direction so as to facilitate and cause the passage of more earth to the rear 35 end of the mold-board in plowing.

The share D has a laterally outwardly and upwardly facing outer surface 45 which is formed between the projecting members 41 and 42 of the share and curved inwardly and 45 transversely and extends forwardly from the forward extremity of the side 43 of the mold-board preferably to the point 40, and said projecting members 41 and 42 diverge outwardly from said surface 45.

To render said side 43 of the mold-board and the surface 45 of the share D capable of cooperating in breaking up or disintegrating lumps of earth passing, during the operation of the plow, from said surface of 55 said share onto said side of the mold-board, the relative arrangement of the parts is such that said side of the mold-board and said surface of said share are flush at the shoulder 36 of the mold-board and that 60 said surface of said share and said side of the mold-board diverge somewhat outwardly from their meeting extremities, as shown in Fig. 5.

Preferably the outer part of the rear end 65 portion of each of the flanges 41 and 42 of

the share D has a forwardly facing and preferably inwardly curved forward edge 46, and hence the forward edge 46 of the flange which is arranged at the top of said share operates to break up or disintegrate 70 any lump of earth that, during the operation of the plow, may be thrown upwardly against said edge and the forward edge 46 of the projecting member which is arranged at the bottom of said share serves to sever 75 roots and participates in breaking up or disintegrating lumps of earth. The rear end portions of the flanges 41 and 42 of the plow-share are preferably considerably 80 wider than the remainder of said flanges, 85 and the forward edge 46 of the outer part of the rear end portion of each flange preferably extends toward the forward extremity of the outer end of said outer part of said portion of the flange so as to materially enhance the efficiency of said portion of said flange. Also, the shoulder 36 on the mold-board is wholly rearward of the earth-disintegrating forward edges 46 of the rear 90 portions of the flanges 41 and 42 so as to minimize, while plowing, undue accumulation or congestion of earth or material on the mold-board next rearward of and in proximity to said shoulder.

My improved hillside plow, by virtue of 95 the hereinbefore described structural peculiarities and relative arrangements of parts, is remarkable for its uniformity of operation and great efficiency in plowing, and is adapted to effect a greater disintegration of 100 lumps of turned-up earth and permit less earth to be thrown upwardly against or above the plow-beam than hillside plows heretofore devised.

What I claim is—

1. A plow comprising a standard, a mold-board arranged in the main at one side of and supported from the standard and having a forward member which extends forwardly of the lower end portion of the standard and has a forwardly facing end face and an upwardly and laterally outwardly facing outer side, and a plow-share seated on said side and extending forwardly of said forward member of the mold-board and having a rear transverse edge at the rear extremity of said side of said member of the mold-board, the mold-board having a forwardly facing shoulder at and opposite said edge of the plow-share and also having an outer side which extends rearwardly from said shoulder and faces upwardly and laterally outwardly, and the plow-share having a rearwardly facing shoulder abutting against the aforesaid face and being secured, between said shoulders, to the aforesaid forward member of the mold-board.

2. A plow comprising a standard, a mold-board arranged in the main at one side of and supported from the standard and hav-

- ing a forward end member which has a forwardly facing end face and an upwardly and laterally outwardly facing outer side, and a plow-share seated on said side of said 5 forward member of the mold-board and firmly secured to said member of the mold-board and having a rear transverse edge, the mold-board having a forwardly facing shoulder at and opposite said edge of the 10 plow-share and also having an outer side which extends rearwardly from said shoulder and faces upwardly and laterally outwardly and is contoured to form a hollow gradually increasing in depth from said shoulder in a rearward direction, and the 15 width of the mold-board being substantially uniform from said shoulder to the rear end portion of the mold-board.
2. A plow comprising a standard, a mold-board arranged in the main at one side of and supported from the standard and having a forward end member which has an upwardly and laterally outwardly facing outer side, and a plow-share seated on said 20 side of said member of the mold-board and having a rear transverse beveled edge at the rear extremity of said side of said member of the mold-board, the mold-board having a forwardly facing shoulder at and opposite said edge of the plow-share and also 25 having an outer side which extends rearwardly from said shoulder and faces upwardly and laterally outwardly, said shoulder being undercut and arranged to form an undercut for and overlapping said edge of the plow-share, the aforesaid member of the mold-board having a forwardly facing end face which is substantially parallel with said shoulder, and the plow-share having a 30 rearwardly facing shoulder abutting against said face and being secured, between said shoulders, to the mold-board.
3. A plow comprising a standard, a mold-board arranged in the main at one side of and supported from the standard and having a forward end member which has an upwardly and laterally outwardly facing outer side, and a plow-share seated on said side of and firmly secured to said member of the mold-board and having a rear transverse edge at the rear extremity of said side of said member of the mold-board, the mold-board having a forwardly facing shoulder which is arranged to form an 40 undercut for and extends longitudinally of said edge of the plow-share and also having an outer side which faces upwardly and laterally outwardly and extends rearwardly from said shoulder, the plow-share having two outwardly diverging flanges which extend and converge from a point adjacent opposite ends respectively of said shoulder toward the forward extremity of the plow-share and are reduced in width toward said extremity, and the outer part of the rear end portion of each flange of said share having a forwardly facing forward edge which extends forwardly toward the forward extremity of the outer end of said outer part of said portion of said flange.
4. A plow comprising a standard, a mold-board arranged in the main at one side of and supported from the standard and having a forward end member which has an upwardly and laterally outwardly facing outer side, and a plow-share seated on said side of and firmly secured to said member of the mold-board and having a rear transverse edge, the mold-board having a forwardly facing shoulder arranged to form an undercut for and extending longitudinally of said edge of the plow-share and also having an outer side which faces upwardly and laterally outwardly and extends rearwardly from said shoulder, the plow-share having two outwardly diverging flanges which extend and converge from a point adjacent opposite ends respectively of said shoulder toward the forward extremity of the plow-share and are reduced in width toward said extremity, the rear end portion of each flange of said share being considerably wider than the remainder of said flange, the outer part of said portion of said flange having a forwardly facing forward edge, and the aforesaid shoulder being wholly rearward of said edge.
5. A plow comprising a standard, a mold-board arranged in the main at one side of and supported from the standard and extending laterally outwardly and upwardly in a rearward direction and having a member extending forwardly of the lower end portion of the standard, and a plow-share seated on and secured to and extending forwardly of said member of the mold-board and having two outwardly diverging flanges which extend endwise of said share and are widest at their rear end portions and converge and are reduced in width toward the forward extremity of said share, the mold- 130

board having an outer side which faces laterally outwardly and upwardly and extends rearwardly from said share and is curved inwardly and transversely, and the outer part of the rear end portion of each flange of said share having an inwardly curved forwardly facing forward edge which ex-

tends forwardly toward the forward extremity of the outer end of said outer part of said portion of said flange. 10

In testimony whereof, I sign the foregoing specification.

MARTIN KELP.
